UNITED STATES PATENT OFFICE.

JAMES WORTH, OF LINEVILLE, IOWA, ASSIGNOR OF ONE-HALF TO ROBERT D. PARKS,
OF ALLERTON, IOWA.

CORN-POPPER.

1,248,234.

Specification of Letters Patent. Patented Nov. 27, 1917.

Application filed July 24, 1914. Serial No. 852,875.

To all whom it may concern:

Be it known that I, JAMES WORTH, a citizen of the United States, residing at Lineville, in the county of Wayne and State of 5 Iowa, have invented new and useful Improvements in Corn-Poppers, of which the following is a specification.

This invention relates to corn poppers and more particularly to portable corn popping cabinets.

One of the principal objects of the invention is to provide a cabinet of the character set forth which is of novel construction and in which the heating element as well as that 15 portion of the popping receptacle supporting the material to be popped will be protected from air currents so as to prevent the conduction of heat away from the receptacle and an unsteady flame from the heating element.

Further objects of the invention will appear as the following description is read in connection with the accompanying drawing, which forms a part of this application, and 25 in which:

Figure 1 is a side elevation.

Fig. 2 is a top plan view, with the cover in table forming position.

Fig. 3 is a vertical section on the line 30 3—3 of Fig. 2.

Fig. 4 is a similar section on the line 4—4 of Fig. 2.

Fig. 5 is a vertical sectional view taken through the popping pot or receptacle.

Referring more particularly to the drawing, 1 represents a suitable running gear of any preferred form and which is preferably supplied with springs 2 upon which the rectangular bottom frame 4 of the cabinet is 35 mounted. Extending vertically from the frame 4 are the corner uprights 5 and the intermediate uprights 6, all of which are joined together by the horizontal bars 7 and by the cross bars 8, 9 and 10. The uprights 40 5 at one end of the cabinet are joined to the uprights 6 by horizontal bars 11 and 12, the latter extending the full length of the cabinet and being connected to the other corner uprights. One side of the cabinet is 45 50 completely covered by any suitable material, such as tin, sheet metal or the like, as indicated at 13, and both ends are covered from the top to the cross bars 8 and 10 by similar material, as indicated at 14. The 55 opposite side is completely covered between

one of the corner uprights 5 and the intermediate upright 6 on the same side by a siding piece 15 which extends from the bottom frame to the horizontal bar 11, and a similar siding piece 16 extends from the 60 opposite corner upright on the same side to the intermediate upright 6 and from the rectangular frame to the lower horizontal bar 7. The space between the lower horizontal bar 7 and the top of the cabinet is 65 closed by a door 17 which is hinged to the vertical upright 6.

The rectangular frame 4 has mounted therein a bottom member 18 upon which are slidably mounted the drawers 19 and 20 operating between the corner uprights, the rectangular frame and the cross bar 8 upon one side and the rectangular frame and the cross bar 10 upon the opposite side. The lower longitudinal bars 7 between the 75 uprights 6 and the uprights 5 at one end of the frame are connected by cross-bars 20' supporting a partition 21 dividing this end of the cabinet into upper and lower compartments, the latter containing said drawer 80 20. The upper longitudinal bars 7 are connected by cross-bars 22 which support a two-part platform practically sub-dividing said upper compartment. The platform is made up of parts or members 23 and 24 85 standing in the same horizontal plane and spaced at their inner edges to leave an opening 25 as best seen in Fig. 4, and within such opening stands a fixed burner 26 whose fluid fuel is fed through a valved pipe from 90 a supply tank 27 as seen. The entire compartment may be closed by the door 17 as seen in Figs. 1 and 4, but when this door is swung open the operator has access to the valve in the fuel supply pipe which is beneath the platform and to the popping mechanism (described below) which is located entirely above the platform whereas the burner stands midway within the opening between the parts of said platform.

Hinged to one of the intermediate uprights 6 at a point 28' within the upper compartment and above the platform therein, is one end of a crane 28 whose body is preferably braced as shown and may swing 95 into the upper division of this compartment. The free end of this crane has a supporting member or horizontal ring 29 upon which the popping pan or kettle 30 is mounted. This kettle is provided with a lid or cover 100 110

31 in which and in the associated bearing arm 32 is journaled a vertical stirrer shaft 33 having stirring fingers 34 upon its lower end. The shaft is also provided with a bevelled pinion 35 which meshes with a similar pinion 36 upon the operating shaft 37. This shaft is journaled in a bracket 38 carried by the cover and a bracket 39 carried by the outer end of the handle 40 of the kettle 10 which is fixed thereto and projects radially therefrom, and said shaft has at its outer end a handle or crank 37' revoluble beyond the end of the radial handle 40.

Thus it will be seen that the corn within 15 the kettle may be agitated in a variety of ways. By grasping the handle 40 the kettle 30 may be rotated or oscillated within its ring-shaped support, by reciprocating the handle longitudinally the kettle and ring 20 can be swung as the crane turns on its pivot or hinge 28', or it is possible that the operator could give the kettle these movements simultaneously. Also by turning the crank handle 37' the stirrer may be moved within 25 the kettle so as to further agitate its contents. Thus an operator standing at the side of the machine has complete control over the burner and a most thorough control over the corn being popped, and the latter 30 need in no case be burned if he exercises ordinary diligence. If his attention is called to the other end of the apparatus, as in making a sale, he can swing open the door 17 and, by drawing on the handle 40, he can 35 swing the crane and popper entirely out of the cooking compartment and away from its position above the flame, and thus cut off the heat temporarily without turning down the burner. But whether he opens the door 40 or not, he can at any time lift the kettle and its charge of cooked corn (without removing the agitator or stirrer), turn it over, and dump the charge into the pan or receptacle 42; after which he recharges the kettle and 45 replaces it in the ring. This pan or receptacle is indicated by the numeral 42 in Fig. 3, and is removably mounted by its flange resting upon cross cleats 41 at the upper end of the cabinet between the upper extremities of 50 one pair of end uprights 5 and those of the intermediate uprights 6, so that the pan is at the top of the structure and adjacent the normal position of the kettle. The pan is provided with a foraminous or screen bottom 43 whose mesh is of sufficient size to pass the unpopped grains of corn which have 55 been emptied therein from the receptacle 30. These grains fall into the drawer 19 from which they may be removed and again

placed in the popping receptacle 30 or 60 thrown away as desired.

Hinged to the upper cross piece 10 is a lid or cover 44 which is adapted to cover the entire cabinet including the receptacle 42 and the burner compartment, and is also adapted 65 to be thrown outwardly to a horizontal position and be supported upon a leg 45 hinged thereto. At this point attention is called to the fact that when the cover 44 is thrown to a closed position the receptacle 42 has been 70 removed and arranged in the drawer 19 and the receptacle 30 inserted in that space previously occupied by the receptacle 42.

In the position of the top or cover shown in Fig. 2 it is adapted to act as a shelf or 75 table for supporting any suitable articles.

What is claimed is:—

1. In a corn popper, the combination with a framework, and a fixed burner therein; of a crane hinged at one end to the framework 80 and having a ring at its other end adapted to swing over the burner, a kettle removably and rotatably supported within the ring and having a fixed radial handle, a cover for the kettle, a rotary stirrer mounted within the 85 kettle, and operating mechanism for the stirrer carried entirely by the cover and the handle and itself having a crank handle at the outer end of said radial handle.

2. In a device of the class described, the 90 combination with a framework having uprights at its corners and intermediate uprights at its sides, a drawer sliding on guides in one end of the framework, a pan supported by the latter above the drawer and 95 having a foraminous bottom, a burner fixedly supported in the other end of the framework and standing in a plane below said pan, and means for supplying fuel to said burner; of a crane hinged at one end to one 100 of the intermediate uprights and having a ring at its other end adapted to swing over said burner, a kettle removably and rotatably supported within the ring and capable of being swung over the burner or out of a position above it as desired, and a handle fixed to said kettle and projecting beyond the contour of the framework whereby the kettle may be moved as described or may be lifted 105 off the ring to dump its contents into the 110 pan.

In testimony whereof I affix my signature in presence of two witnesses.

JAMES WORTH.
